CHILD'S TOILET SEAT

Paul E. Jack, Englewood, Colo.

Application March 7, 1949, Serial No. 79,970

5 Claims. (Cl. 4—239)

1

This invention relates to a child's toilet seat, and has for its principal object the provision of a child's toilet seat structure which will fold completely into the lid of a conventional toilet seat without increasing the size or thickness of the conventional lid.

Another object of the invention is to so construct the device that, when the conventional seat is desired for use, it is only necessary to lift the lid in the usual way, without interference from the child's seat structure, and, when it is desired to use the child's seat, it is only necessary to lift a portion of the lid to bring a complete child's seat, with arm rests, into position for use.

A further object of the invention is to so construct the device that the existence of the child's seat structure will not be apparent to the casual toilet user, and to provide a child's seat structure which can be entirely covered by the usual ornamental fabric toilet lid cover when not in use.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a plan view of the improved child's toilet seat;

Fig. 2 is a longitudinal section therethrough, taken on the line 2—2, Fig. 1;

Fig. 3 is a plan view, illustrating the improved seat in the open position;

Fig. 4 is a side view of the open child's seat;

Fig. 5 is a detail, enlarged section, taken on the line 5—5, Fig. 1; and

Fig. 6 is a similar detail section, taken on the line 6—6, Fig. 3.

In the drawing, a conventional toilet bowl is indicated at 10, with its standard seat at 11 mounted on the usual seat hinge 12.

The improved child's seat consists of a child's seat 13 having a shape and contour corresponding to that of the usual toilet seat lid and adapted to be mounted on the hinge 12 in the place of and similarly to the standard lid. The child's seat is provided with a hole 14 of children's size, and is formed with hinge lugs 15 rearwardly of the hole 14 to which a child's lid 16 is hinged by means of a hinge pin 26.

2

The forward extremity of the child's lid 16 conforms in shape to the contour of the child's seat 13. The rear extremity is preferably straight so as to provide alignment with the hinge 15. The lid 16 is surrounded on its two sides and rear by means of a U-shaped member 17, the sides of which also conform in shape to the shape of the seat 13 and extend forwardly on each side of the lid 16 to form two integral arm rests 18. The U-shaped member 17 is mounted upon a second set of hinge lugs 19, formed along the back of the seat 13, by means of a hinge pin 27. The total thickness of the child's lid 16 and the U-shaped member 18, plus the thickness of the child's seat 13, is equal to the thickness of the usual toilet seat lid which is replaced by the present invention.

The lid 16 is provided with two outwardly extending pins 20 which ride in grooves 21 in the arm rests 18. Thus, when the lid 16 is raised about its hinge pin 26, the pins 20 will travel along the grooves 21 and act to raise the arm rests 18 until the lid rests against the rear portion of the U-shaped member 17, as shown in Fig. 4. The pins 20 now act to support the arm rests at a comfortable, convenient incline. The lid 16 is also braced and supported by the U-shaped member 17 at a slight rearward incline to provide a convenient and comfortable back rest for the child.

A splash plate 22 is mounted upon a hinge pin 23 below the front of the hole 14. The splash plate has an upwardly extending, relatively thin portion 24 which, when the seat is folded, rests in a conforming depression 25 in the seat 13. The lower portion of the splash plate is relatively thick so as to provide weight which will automatically swing the entire splash plate downwardly and forwardly, as shown in Fig. 4, when the lid 16 is lifted therefrom.

It can be seen from the above that if it is desired to use the regular seat 11, it is only necessary to lift the child's seat 13, causing the entire child's seat structure to rise as a conventional lid unit. If it is desired to use the child's seat, it is only necessary to lift the lid 16, which will automatically bring the arm rests, back rest, and splash plate into position. Should the conventional seat 11 be lifted when the child's seat is in the open position, no harm will result, since the child's seat 13 will simply fold back against and receive the child's lid 16.

It is preferred to reinforce the grooves 21, especially when formed from plastic, by placing

a metal insert 28 in the plastic to form the outline of the groove 21.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. A toilet seat for children comprising: a seat 10 having a toilet opening; a relatively flat, U-shaped member resting upon and extending across the back and forming arms along the two sides of said seat; a hinge securing the rear extremities of said seat and said U-shaped member together; a lid hinged upon said seat forwardly of said hinge and rearwardly of said toilet opening, said lid adapted to lie upon said seat between said arms and forming, in combination with said U-shaped member, a complete cover for said seat conforming in shape thereto; and means for causing said U-shaped member to swing upwardly to form arm rests when said lid is swung upwardly to form a backrest.

2. A toilet seat for children comprising: a seat having a toilet opening; a relatively flat, U-shaped member resting upon and extending across the back and forming arms along the two sides of said seat; a hinge securing the rear extremities of said seat and said U-shaped member together; a lid hinged upon said seat forwardly of said hinge and rearwardly of said toilet opening, said lid adapted to lie upon said seat between said arms and forming, in combination with said U-shaped member, a complete cover for said seat conforming in shape thereto; pins projecting oppositely outward from said lid adjacent the hinged rear extremity thereof; and means on said U-shaped member slidably receiving said pins so as to cause the arms of said U-shaped member to swing upwardly to form arm rests when said lid is swung upwardly to form a seat.

3. A toilet seat for children comprising: a seat having a toilet opening; a relatively flat, U-shaped member resting upon and extending across the back and forming arms along the two sides of said seat; a hinge securing the rear extremities of said seat and said U-shaped member together; a lid hinged upon said seat forwardly of said hinge and rearwardly of said toilet opening, said lid adapted to lie upon said seat between said arms and forming, in combination with said U-shaped member, a complete cover for said seat conforming in shape thereto; pins

projecting oppositely outward from said lid adjacent the hinged rear extremity thereof; and means on said U-shaped member slidably receiving said pins so as to cause the arms of said U-shaped member to swing upwardly to form arm rests when said lid is swung upwardly to form a seat, said U-shaped member contacting the back of said lid when the latter is in the backrest position to form a brace therefor.

4. The combination, with a standard toilet seat and its hinge, of a child's seat mounted on said hinge and extending forwardly over said standard seat; a second hinge at the rear of said child's seat; a relatively flat, brace member mounted on said second hinge and extending forwardly over said child's seat; arm rests extending forwardly from said brace member along each side of said child's seat; a third hinge on said child's seat positioned forwardly of said second hinge; a lid hinged on said third hinge and extending forwardly over said child's seat between said arm rests and forming, in combination with said brace member and said arm rests, a complete cover for said child's seat; and projections extending oppositely outward from said lid and slidably engaging in said arm rests so that the latter will be elevated when said lid is swung upwardly about its hinge.

5. A toilet seat for children comprising: a seat 30 having a toilet opening; a relatively flat, U-shaped member resting upon and extending across the back and forming arms along the two sides of said seat; a hinge securing the rear extremities of said seat and said U-shaped member 35 together; a lid hinged upon said seat forwardly of said hinge and rearwardly of said toilet opening, said lid adapted to lie upon said seat between said arms and forming, in combination with said U-shaped member, a complete cover for said seat 40 conforming in shape thereto; means for causing said U-shaped member to swing upwardly to form arm rests when said lid is swung upwardly to form a backrest; and a splash plate hinged upon said seat at the forward edge of the opening 45 therein, said plate extending above and below said seat, the part extending below being heavier than the part extending above, and there being a depression in said seat in which the part extending above is held by the weight of said lid 50 when the latter is closed.
